UNITED STATES PATENT OFFICE.

LUKE W. FARMER, OF SOMERVILLE, MASSACHUSETTS.

FLANGING DEVICE FOR PAPER DRINKING-CUPS.

1,082,687.

Specification of Letters Patent. Patented Dec. 30, 1913.

Application filed August 23, 1912. Serial No. 716,583.

To all whom it may concern:

Be it known that I, LUKE W. FARMER, a citizen of the United States, residing at Somerville, in the county of Suffolk and State of Massachusetts, have invented an Improvement in Flanging Devices for Paper Drinking-Cups, of which the following is a specification.

In the manufacture of paper drinking-cups, it is desirable to form an outward flange at the top of the cup; and this invention has for its object the construction of a simple device for this purpose.

The device comprises essentially a hollow rotatable cup-holder, into which the cup is placed, which is made shorter than the cup, so that the top of the cup will project a short distance above it, and a flanging-tool which is supported on a standard at the side of said cup-holder, and movable about a horizontal axis to admit of the tool being tilted in an upward direction to pass over the top of the cup, so as to occupy a position at the inside thereof, and is also movable about a vertical axis to admit of its being swung in a horizontal plane, to bend the top of the cup outward over upon the top of the cup-holder, thereby to form the flange.

Figure 1 is a side elevation of a cup-flanging device embodying this invention. Fig. 2 is a plan view of the same. Fig. 3 is a sectional detail of the flanging-tool and a portion of the cup-holder. Fig. 4 is a side elevation of the flanged cup.

10 represents a hollow cup-holder, of conical form, to receive a paper cup to be flanged. It is secured to a rotatable spindle 12, whereby it is rapidly rotated. It is made shorter than the cup, so that the top of the cup when contained therein will project a short distance above it, see Fig. 1, such distance being equal to the width of the flange which is to be formed.

14 represents an upright standard or post, which is arranged at the side of the cup-holder. A block or head 15 is swiveled to the top of the standard 14, thereby to enable it to be turned on a vertical axis, and said block has a pair of ears between which the shank of the flanging-tool is placed, and said tool is pivotally connected to said ears by a pin 16 passing through the ears and the shank of the tool. Said pivot-pin 16 is arranged horizontally, thus admitting of the flanging-tool being moved about a hori-

zontal axis, and as the block bearing said tool is movable about a vertical axis the flanging-tool is likewise movable.

The flanging-tool comprises a shank 20, 60 having a flange-forming portion at its forward end, made as a finger 21 which is made convex on its under side and preferably convex on its upper side, see Fig. 3, and is inclined at its extremity, or curved upwardly, 65 see Fig. 1, and said shank has a handle 22 at its rear end adapting it to be engaged by hand for the purpose of manipulating the tool.

In operation, a paper cup to be flanged is 70 placed upside down in a shallow pan of water, thereby to saturate its top, which portion thereof is to be turned outward to form the flange; then the cup is placed in the cup-holder in upright position with its 75 top projecting a short distance above it; then the flanging-tool is engaged by hand and its finger 21 is raised and moved over the top of the cup into a position in the line of a chord of the arc thereof, and is 80 then depressed and brought into engagement with the projecting portion or edge of the cup at the inside thereof, and is then moved outward to bend the edge of the cup in an outward direction over upon the top 85 of the cup-holder while the cup-holder bearing the cup rotates, thereby to form the flange. All of these motions may be given to the tool by manipulating the handle. By reason of the arrangement of the fingers 90 as here shown in the line of a chord of the arc of the cup edge when in engagement therewith, the edge of the cup convergently or obliquely engages the finger, although in addition thereto said edge of the cup convergently engages the convex face of the finger. 95

I claim:

1. A flanging-device for paper drinking cups consisting of a rotatable hollow cup-holder made shorter than the cup, permitting the top of the cup to project above it a short distance, a flanging-tool supported at the side of the cup-holder having a flanging-finger with a convex under side arranged to 100 be extended over the edge of the cup on the line of a chord of the arc thereof, whereby the edge of the cup convergently engages said finger, said tool being movable to move the finger into and out of engagement with the 105 edge of the cup, substantially as described.
2. A flanging-device for paper drinking

- cups consisting of a rotatable hollow cup-
holder made shorter than the cup, permitting
the top of the cup to project above it a
short distance, a flanging-tool supported at
5 the side of the cup-holder having a flanging-
finger with an upwardly curved end-portion
and with a convex under side arranged to be
extended over the edge of the cup on the
line of a chord of the arc thereof, whereby
10 the edge of the cup convergently engages said
finger, said tool being movable to move the
finger into and out of engagement with the
edge of the cup, substantially as described.
3. A flanging-device for paper drinking
15 cups consisting of a rotatable hollow cup-
holder made shorter than the cup, permitting
the top of the cup to project above it

a short distance, a flanging-tool, a block
swiveled to the upper end of a standard ar-
ranged at the side of the cup-holder to which 20
said tool is pivoted, whereby said tool may
be given four motions to pass over the top
of the cup without engaging it, and to en-
gage the top of the cup upon return move-
ment, said tool having means as a handle by 25
which said four motions may be given to it.

In testimony whereof, I have signed my
name to this specification, in the presence of
two subscribing witnesses.

LUKE W. FARMER.
